MARK K. BOWMAN, OF MONTCLAIR, NEW JERSEY.

APPARATUS FOR CLEANING BOILER-TUBES.

1,325,348.

Specification of Letters Patent. Patented Dec. 16, 1919.

Application filed June 11, 1919. Serial No. 303,425.

To all whom it may concern:

Be it known that I, MARK K. BOWMAN, a citizen of the United States, and resident of Montclair, in the county of Essex and State of New Jersey, have invented certain new and useful Improvements in Apparatus for Cleaning Boiler-Tubes, of which the following is a specification.

My present invention is an improved device of the above type whereby in one operation a dirty boiler tube may be rough-scraped, wire-brushed, wiped and air dusted, perfectly cleaned, by a single pass of the cleaner. It will be understood, however, that in special cases, as where the tube is rusted or the deposit otherwise hardened in place, there is no reason why repeated passes of the cleaner should not be made.

My invention for this purpose may be more fully understood from the following detailed description in connection with the accompanying drawings, in which—

Figure 1 is a side elevation of a boiler of ordinary type broken away to show one of the tubes in longitudinal section, with the cleaner and propelling apparatus applied thereto;

Fig. 2 is a vertical longitudinal section of the cleaner taken on the line 2—2 of Fig. 3; and

Fig. 3 is a rear end elevation of the cleaner.

As shown in these drawings the cleaner comprises a front scraper disk 1 of slightly less diameter than the tube to be cleaned, a wire brush 2 in the rear of said scraper of slightly greater diameter than said tube and in the rear of the brush a cup washer 3 preferably of leather of less diameter than the brush but of greater diameter than the scraper and preferably fitting the tube to be cleaned.

The above essential elements are structurally united and held concentric with a single axis by suitable means. As shown in the drawings, the brush and scraper are in the form of a separable reversible unit resembling a spool against one end of which the cup washer 3 is clamped by bolt 4 extending through the spool and cup washer clamping disk 5. The brush and scraper unit preferably comprises a tubular body portion 6 having the disk 1 secured at one end and the similar disk 1^a at the other end thereof. One or both of these disks may be screw-

threaded to permit application and removal of the cylindrical wire brush 2.

Wire brush 2 preferably consists of wire bristles bent around and pinched between the turns of a helical spring 7.

I preferably provide a clearance space as shown between the brush wires and the end disks 1, 1^a. The clearance behind disk 1 affords space for considerable accumulation of soot, etc., before there will be any tendency to press the brush wires backward. The clearance space between the brush wires and disk 1^a permits the rearmost wires to bend rearwardly the maximum amount required without danger of causing them to bend too sharply around the edges of said disk 1^a.

The wire bristles of the brush are quite long and are protected for a considerable portion of their length by the scraper 1 for the purpose and with the result that when passing through a dirty tube, they cannot be bent backward sharply enough to produce an immediate permanent set as might otherwise be the case. Nevertheless, even with the proportions shown, the wire tips quickly become worn off on a smooth bevel and, with the inferior springiness of materials commonly available for this purpose, are apt to take a certain amount of set particularly when used on very dirty tubes. When this occurs, it is only necessary to remove bolt 4, reverse the spool so that disk 1 becomes a washer clamping disk and disk 1^a the advance scraper disk. Similar reversal may be resorted to if the disk 1 becomes bent or worn by use.

The construction shown permits of easy and quick renewal of either disk or of the brush or of the cup washer whenever any of them become worn or damaged.

The above described cleaner is forced by hand or suitable tool a short distance into one of the tubes 10 of the boiler 11. Behind it is then inserted nozzle 12 connected by pipe 13 with a compressed air supply 14 controlled by valve 15 and also by a valve 15^a at the nozzle. The nozzle 12 may be provided with an exterior rubber packing to make it fit the tube tightly if desired, but where considerable air pressure, say 90 pounds, is available, the impact of the air jet will be sufficient to drive the cleaner through even a dirty tube at extremely high velocity.

When so driven, the tube is rough-scraped by disk 1, clean-brushed by brush wires 2, wiped by cup washer 3 and finally blown clean by air blast from 12.

- 5 The high velocity operation is particularly desirable since in such case the projectile quality (momentum times the square of the velocity) will easily carry the projectile through badly obstructed points in 10 the tube where a slow moving cleaner would stick.

The smaller diameter of front disk 1, the 15 flexibly changeable diameter of the brush wires 2, and the longitudinal flexibility of the cup washer, all coöperate to give the device special facility for guiding itself around bent portions of the tubes of water-tube boilers.

- I claim:
20 1. A tube cleaning projectile of the class described, comprising a piston and wiper element, a cylindrical wire brush element

in advance of the piston element, and a radially projecting disk between the piston element and the brush element, the brush 25 element being of greater diameter, and the disk of smaller diameter than the piston element, said brush element, being spaced such material distance from the disk as will permit the brush elements to overlap the 30 disk.

2. A tube-cleaning projectile of the class described, comprising a piston element and a brush element, the brush element consisting of a cylindrical wire brush and a spool- 35 like member on which the latter is supported having similar radially projecting scraper disks at its ends, in combination with means for reversibly securing said spool to said piston element. 40

Signed at New York city, in the county of New York and State of New York, this 9th day of June, A. D. 1919.

MARK K. BOWMAN.
